NONSKID WALKING SPUR

Albert Hall, Philadelphia, Pa.

Application June 10, 1944, Serial No. 539,744

2 Claims. (Cl. 36—62)

My invention relates to non-skid walking spurs, and relates particularly to a device which can be readily attached or detached from the heel of a shoe at will.

It is an object of my invention to provide a non-skid device for shoes which may be used when walking or traveling on snow, ice, on the soil, or grass.

It is also an object of my invention to provide a device of the character described which is simple in construction and which may be manufactured at a slight cost.

It is a further object of my invention to provide an underfoot gripping member which may be applied to men's, women's, or children's shoes.

Another object of my invention is to provide a non-skid walking spur which is symmetrically constructed so that it may be equally adapted for use when applied to either a left or right shoe.

Other objects of my invention are to provide an improved device of the character described, that is easily and economically produced, which is sturdy in construction and which is highly efficient in operation.

With the above and related objects in view, my invention consists in the details of construction and combination of parts, as will be more fully understood from the following description when read in conjunction with the accompanying drawing, in which

Fig. 1 is a side elevational view of a non-skid spur embodying my invention as applied to the heel of a shoe.

Fig. 2 is a bottom view of the non-skid walking spur.

Fig. 3 is an end view of the spur.

Fig. 4 is a side elevational view of a modification of a walking spur embodying my invention as applied to a woman's shoe.

Fig. 5 is a bottom view of the modification of the spur as illustrated in Fig. 4.

Fig. 6 is a rear end view of the spur shown in Fig. 5.

Fig. 7 is a bottom view of the walking spur of Fig. 5 showing the spur in reversed position on the outline of a heel.

Referring now in detail to the drawing, in which like reference characters indicate corresponding parts throughout, a heel of a shoe is indicated as 10 and a non-skid walking spur embodying my invention is indicated generally as A. The spur A is constructed of a single piece or strip of stiff rod or wire and it is formed to comprise a central main shank portion 12 which is adapted to rest or bear against the ground.

From the main shank portion 12, the wire is bent outwardly to form short arms 14, 16 which may bear or rest against the inner or shank portion of the heel 10, and the arms 14, 16 are located beneath the shank of the shoe. Contiguous with short arms 14, 16 are long arms, or sides, 18, 20 bent to rest against the sides of the heel 10 of the shoe.

The sides 18, 20 extend to the back of the heel. They bend downwardly at 19 and 21 and then are offset at 22, 24 to rest directly under the heel 10. From the heel touching portions 22, 24 are downwardly extending members or points 26 and 28, respectively, whose dull points 30 and 32 engage the underfoot surface.

The sides 18, 20 appear in one horizontal plane which I shall designate the top horizontal plane; the offset portions 22, 24 appear in a horizontal plane spaced from the top horizontal plane, the points 26 and 28 are positioned in a vertical plane, and the central portion 12 appears in a plane inclined about 45° to the top horizontal plane, but beneath the top horizontal plane when the top horizontal plane is extended.

The center 12 of the rod A is inclined at an angle of approximately 45° so that it is beneath the shank of the shoe and it is low enough to be on the level with the points 26 and 28 so that there is a three-point rest for the spur A. A serration or gripping slot 34 may be placed on the bottom of the central portion 12 of the spur in order to firmly grip the ground, ice or snow, or any other slippery surface.

It is to be noted that the offset ends 22, 24 of the spur A are spaced apart so that there exists a certain degree of resiliency so that the spur may be placed upon the heel of the shoe by pulling on the resilient ends 22, 24 which are contiguous to the long arms 18, 20. Hence, the resilient long arms 18, 20 of the clamping portion fit closely around the sides of the heel. The points 26 and 28 form bearing points which serve to effectually hold the creeper from displacement with respect to the ice, soil, or snow. The central shank portion 12 has a depression or ridge 34 therein to serve as an additional holder.

To detach the spur, it is only necessary to push upon extension 36 on the arm 20 or to push one of the long arms downwardly and forwardly, or spread one of the clamping portions laterally, so the spur A can readily and easily be removed. I place a plate or extension 36 so that the foot on which the spur is not placed may be used to push against the extension or plate 36 to slide the spur from the heel of the shoe.

It is to be noted that my spur has a three-point contact; it has a kick-off plate or extension; it has an extension loop; and it has a stop effect.

A spur, generally designated as B, is adaptable for very high ladies' heels, and it is constructed similarly to the spur A for men's shoes. The central main part 12 of the wire or rod of which the spur is formed as an integral unit has a serration or slot 34 therein and the central part 12 rests beneath the heel. The ends of the central main portion 12 of the spur B are bent to form two parallel horizontally extending arms 40 and 42 which directly bear against the bottom of the heel. The other ends of the supporting arms 40 and 42 are turned to join contiguous vertical arms 41 (one arm 41 only being shown in the drawing) whereby the vertical arms 41 are formed to join long side arms 18 and 20. The arms 22 and 24 and the points 26 and 28 are similarly constructed in men's and women's type of walking spurs.

In Fig. 5, I show the walking spur as applied to the outline of a heel whereby the points are to the rear and the third portion is to the front of the heel.

In Fig. 7, I show the walking spur B reversed from the position of Fig. 5, wherein the pointed ends are at the front of the heel and the central portion of the spur is at the rear of the heel. I consider the change in location to be advisable depending on the conditions under which the spur is worn.

It is apparent in view of the aforementioned detailed description and described function of my invention that the device may be formed in a press; there is no welding of parts which other-

wise would involve costly operations; and that the spur affords protection to persons who must walk on the ice or snow, or to persons who walk upon the grass or soil, such as golfers.

Although my invention has been described in considerable detail, such description is intended as illustrative rather than limiting, since the invention may be variously embodied, and the scope of the invention is to be determined as claimed.

I claim as my invention:

1. A walking spur comprising a single metallic rod deformed to provide two spaced long arms adapted to press against the sides of a shoe heel, a central connecting portion extending at an inclined angle to the plane in which said long arms are located and being lower in position than said long arms, two substantially vertically extending portions to grip the ground, and said central connecting portion being adapted to be in the ground plane to form a three point ground gripping spur.

2. A walking spur comprising a single metallic rod deformed to provide two spaced long arms adapted to press against the sides of a shoe heel, a central connecting portion extending at an inclined angle to the plane in which said long arms are located and being lower in position than said long arms, two substantially vertically extending portions to grip the ground, said central connecting portion being adapted to be in the ground plane to form a three point ground gripping spur, an extension on one of said long arms extending outwardly whereby said extension may be pushed by the wearer in order to remove said spur.

ALBERT HALL.
